TEACHING MACHINE IN THE FORM OF A STUDENT RESPONSE BOARD

Leonard N. Albrecht, Mill Valley, Calif., assignor to
Dymedia, Inc., Palo Alto, Calif., a corporation of
California

Filed Oct. 31, 1968, Ser. No. 14,257

Term of patent 14 years

Int. Cl. D19—08

U.S. Cl. D25—1

FIG. 1

FIG. 2

FIG. 3

FIG. 4

FIG. 5

FIG. 1 is a perspective view of my design;
FIG. 2 is a plan view of my design.

FIG. 3 is a side elevational view of my design the
reverse side being a substantial mirror image thereof;

FIG. 4 is an end view taken from the left end of FIG.
3; and

FIG. 5 is an end view taken from the right end of
FIG. 3.

The essential features of my design are shown in full
lines.

I claim:

The ornamental design for a teaching machine in the
form of a student response board, as shown and de-
scribed.
